CLAIM

The ornamental design for a piston for a refrigerant compressor, as shown and described above.

DESCRIPTION

FIG. 1 is a left side view of a piston for a refrigerant compressor, according to the design. The right side view is a mirror image of the left side view.

FIG. 2 is a front view of the piston for a refrigerant compressor, as shown in FIG. 1.

FIG. 3 is a top view of the piston for a refrigerant compressor, as shown in FIG. 1.

FIG. 4 is a bottom view of the piston for a refrigerant compressor, as shown in FIG. 1.

FIG. 5 is a rear view of the piston for a refrigerant compressor, as shown in FIG. 1.

FIG. 6 is a cross-sectional view of a refrigerant compressor taken along the line 6—6 of FIG. 1;

FIG. 7 is a cross-sectional view of the refrigerant compressor taken along the line 7—7 of FIG. 1;

FIG. 8 is a cross-sectional view of the refrigerant compressor taken along the line 8—8 of FIG. 1; and,

FIG. 9 is a rear perspective view of the piston for a refrigerant compressor of FIG. 1.
